UNITED STATES PATENT OFFICE.

CHARLES E. RICE, OF OWENSBOROUGH, ASSIGNOR OF ONE-HALF TO JOHN C. SCHRADER, OF DAVIESS COUNTY, KENTUCKY.

HEMMER FOR SEWING-MACHINES.

SPECIFICATION forming part of Letters Patent No. 253,766, dated February 14, 1882.

Application filed October 27, 1879.

To all whom it may concern:

Be it known that I, CHARLES E. RICE, a citizen of the United States, residing at Owensborough, county of Daviess, and State of Kentucky, have invented a new and useful Improvement in Sewing-Machine-Hemmer Attachments, of which the following is a specification.

My invention relates to hemmers for sewing-machines, and is so arranged in parts that it can be attached to any machine and produce a hem of any desired width. I attain these objects by the mechanism illustrated in the accompanying drawings, in which—

15 Figure 1 is a side elevation. Fig. 2 is a plan view of the two plates and connecting means. Fig. 3 is a section through the thumb-screw, shank, and upper plate. Fig. 4 is a side view of the slotted attachment-bar. Fig. 5 is a perspective of my hemmer and attachment-bar. Fig. 6 is a longitudinal sectional view of the same.

Similar letters refer to similar parts throughout the several views.

25 In the accompanying drawings, A is a thumb-screw attached to the threaded shank or standard h. B is the under plate. C is the fabric-presser, that passes partly under the front end of the presser-foot of the machine. E is the forward bent end of the under plate, B, which is designed to turn under the edge of the fabric passing through it. H is the longitudinal slot in the extension P' of the upper plate, P. L is a slotted bar, held to the hemmer by the thumb-screw A. By means of said bar the device is attached to the machine. P is the upper plate, one end of which is turned under the ear E on the under plate, B. P' is the rear extension of the upper plate, P. T is a graduated scale on the extension P' of the plate P.

In the small letters, a is a slot through the vertical center piece in the under plate, B. e is the lapped end of the tongue i, which passes 45 through a slot in the vertical portion of the bar

P. Said end is soldered and fixed thereto. i is the tongue, fixed at e, passing through the slot a in the bar B, and holds the semicircular guide g. f is the slot in the bar L. h is the screw-shank, over which the cap or thumb-screw fits. m is a strap, formed from metal, lapped over from the under plate, B. Said strap encircles the rear extension, P', of the upper plate, P.

This hemmer can be firmly attached to any 55 machine by means of the slotted bar L and thumb-screw A. The slotted bar is designed to connect with a thumb-screw or attachment device of a sewing-machine.

By constructing my hemmer in two pieces 1 60 I am enabled to produce a hem of any width, by reason of the two parts being adjustably attached, one over the other. They connect at the thumb-screw by means of the strap m, which forms an adjustable slide on the graduated 65 scale T. By moving the strap m oversaid scale the width of the hem is varied, so as to suit the convenience of the operator.

Having thus described my invention, I claim as new and desire to secure by Letters Patent— 70

1. A hemmer for a sewing-machine, consisting essentially of the plate B, having the bent end or ear E, presser C, screw-shank h, and strap m, in combination with the plate P, having slotted extension P', provided with a graduated scale, T, and tongue i, having guide g, substantially as described. 75

2. A hemmer for a sewing-machine, consisting of the plate B, having bent end E, presser C, screw-shank h, and strap m, also the plate 80 P, having slotted extension P', provided with a graduated scale, T, and tongue i, having guide g, in combination with the thumb-screw A and slotted bar L, substantially as described, and for the purposes set forth.

CHARLES E. RICE.
